UNITED STATES PATENT OFFICE.

PHILIP T. SHARPLES, OF MERION, PENNSYLVANIA.

REFINING OIL.

1,416,891.

Specification of Letters Patent. Patented May 23, 1922.

No Drawing. Continuation of application Serial No. 495,083, filed August 24, 1921. This application filed April 6, 1922. Serial No. 550,206.

To all whom it may concern:

Be it known that I, PHILIP T. SHARPLES, a citizen of the United States, residing at Merion, in the county of Montgomery and 5 State of Pennsylvania, have invented certain new and useful Improvements in the Refining of Oil, of which the following is a specification.

This invention is a method which effects 10 the refining of mineral oil so as to produce large yields of superior products, with avoidance of the destructive actions that result in the methods heretofore practiced, particularly in the separation of wax from lubricating distillates and this application is a 15 continuation of my application, filed August 24, 1921, Serial Number 495,083, as to all matter common to the two applications.

A specific desideratum effected is the removal of wax from certain lubricating distillates without the cracking distillation which has been practiced heretofore to effect the so called "crystallization" of such wax as an essential step in its removal and which 25 cracking has resulted in the reduction of the viscosity, the value and the yield of lubricating oil.

It is to be understood that the wax in such lubricating distillates is in an "intermediate" 30 condition between the so called "amorphous" wax and the so called "crystalline" wax. Wax in the "intermediate" form clogs a filter so that it cannot satisfactorily be pressed, does not respond in any satisfactory manner 35 to the cold settling treatment, and it has not been practicable to separate it by centrifugal force successfully by known methods, so that heretofore it has been considered to be commercially impracticable, if not altogether im- 40 possible, to remove this wax from the oil without subjecting the oil and the wax to a treatment which changes the physical characteristics of the wax, but which incidentally changes the physical characteristics of the 45 oil so as greatly to reduce the value thereof.

In accordance with my invention in the preferred practice thereof, the lubricating constituents of the oil are distilled off so as to avoid substantial cracking or substantial 50 injury to the oil and as much of the oil as practicable is taken in a cut which will contain primarily the so-called "crystalline" wax, which wax can be removed by filter

pressing. The cut which follows contains wax in what I term the "intermediate" state, 55 but it is to be understood that my invention relates to the treatment of oil containing such wax irrespective of the manner in which the fraction of oil is obtained. An example of a type of material which contains wax 60 in the intermediate state is the "34 stock" - so-called by reason of the gravity at which a cut is taken which corresponds approximately to 34° Bé.

This lubricating distillate or stock, containing wax in the "intermediate" form, is now specially treated for the removal of wax, by dilution with naphtha so as to reduce the density of the oil relatively to the wax, chilling the product so as to precipitate 70 the wax while maintaining the fluidity of the oil and centrifuging in a special manner, so as to continuously separate and separately discharge the wax and the wax free oil, preferably by the use of a carrier liquid for float- 75 ing off the wax.

The treatment is applied to the stock directly or to a residue obtained by distilling off say 35% of a cut such as the "34 stock", without substantial cracking, as distin- 80 guished from the distillation of the bulk thereof with its accompanying deterioration of the oil found unavoidable in the prior practice of removing the wax, particularly from the more viscous and valuable frac- 85 tions.

I effect the dilution by using enough naphtha to prevent the oil from becoming solid or semi-solid upon chilling by the use of a diluent of such light character and large 90 excess as to increase the difference in gravity between the oil and wax so that they can be separated and separately discharged continuously in a centrifugal operation after precipitation of the wax by appropriate chilling. 95 The wax in the "intermediate" form, in which it is found in the lubricating distillate that has not been subjected to the objectionable destructive distillation, will absorb a certain amount of naphtha with 100 consequent reduction of its specific gravity as well as that of the oil, so that in the treatment for centrifugal separation there should be not merely dilution but dilution beyond the saturation of the wax or dilution that 105 results in such difference in specific gravity

between the constituents that they can be centrifugally separated. In general I have found it advisable to use 70% of naphtha of a specific gravity corresponding to 65° Bé. but the amount of such naphtha used may vary somewhat with different types of oil.

The chilling of the diluted oil to precipitate the wax is effected by means of chilling 10 surfaces that are kept clean by the constant removal of deposits of wax therefrom without agitation of the oil violently or more than is necessary, for the desired regular chilling is not effected through wax which 15 deposits on the cooling surfaces and violent agitation of the oil tends to disseminate the wax therethrough and cause the whole mixture to set as a jelly. Consequently, the chilling surfaces should be scraped regularly but slowly and without substantial agitation of the oil. To obtain good results 20 it generally is necessary to chill to a temperature of 0° F. and I prefer to chill to a temperature of about -10° F.

25 The oil having been chilled and the wax precipitated, the separation is effected centrifugally, preferably in a centrifuge containing a carrier liquid, which is desirably water that is held in the bowl against the 30 wall thereof so that the separated wax will float off thereon, though a different carrier liquid such as brine may be used and the carrier liquid may flow through the bowl in accordance with known operations, as described in my U. S. Patent No. 1232104.

I have found that water is satisfactory as a carrier liquid and will not freeze even when centrifuging oil chilled to below zero, the air friction on the bowl shell keeping 40 the temperature of the water above its freezing point. Water has the advantages of low cost, convenient supply and has much less tendency to corrode the centrifugal than brine or most other aqueous carrier liquids. 45 In addition its specific gravity is more nearly that of the wax than brine or other practicable aqueous solutions and the adjustments required of the centrifuge are therefore less delicate.

50 In the indicated specific application of my method to the treatment of "34 stock" by distilling off 35%, I use fire and steam to effect the distillation so as to avoid substantial cracking, treat the residue remaining 55 in the still with 70% of 65° Bé. naphtha having a close range of boiling points, heat to dissolve the wax, chill in contact with chilling surfaces which are scraped about once in ten minutes without agitating the 60 oil, which is thus cooled to -10° F., and pass the mixture through the rotor of a suitably designed centrifuge (such for instance as shown in my U. S. Patents Nos. 1232104 and 1401196) and containing water as a carrier liquid, the wax separated from the oil 65

being floated off on the carrier liquid and the wax free oil being separately discharged, continuously.

A typical operation of my process as applied to an oil having a paraffin base, is 70 shown by the following diagram:

75

80

85

In this particular example four times as much heavy lubricating oil (300 second universal Saybolt viscosity at 100° F.) has been produced by my method here disclosed as by the approved practice in general use.

In handling crude oil having an asphaltic base, now commonly distilled with fire to coke, I prefer to distill according to the same procedure as is ordinarily used with a crude oil having a paraffin base, excepting 90 that the 15% residue would be further distilled with cracking to secure a greater recovery of lubricating oil. I can thus obtain much more heavy lubricating oil from the same crude.

95

It is to be understood that in its broad aspects my invention is quite independent of the type of machine that is used or the details of operation and my claims of novelty are based upon my discovery that it is possible to treat a mixture of lubricating oil and wax intermediate the so-called "crystalline" and "amorphous" forms and separate the wax from the oil by a continuous centrifugal operation.

100

Having described my invention, I claim:

1. The method of treating the residue obtained by distilling off lower boiling point constituents from crude petroleum which consists in distilling the residue so that the oil shall not be cracked substantially, treating the distillate to effect the precipitation of the wax and maintain the fluidity of the oil so that they can be separated by centrifugal force, and centrifugally separating and 110 separately discharging the wax and the wax freed oil continuously.

115

2. The method of treating the residue obtained by distilling off lower boiling point constituents from crude petroleum, which consists in distilling the residue so that the oil shall not be cracked substantially, diluting the distillate with a solvent of lower specific gravity that will reduce the density of the oil relatively to that of the wax, chilling the diluted product so that the wax shall be precipitated and the oil maintained in fluid condition, and centrifugally separating and separately discharging the wax and the wax freed oil continuously.

120

125

130

3. The method of treating the lubricating residue obtained by distilling off the lower boiling point constituents of crude petroleum, which consists in steam distilling and fractionating said residue without substantial cracking, diluting a fraction or fractions with a lower boiling point petroleum product, chilling the fractions so that the wax shall be precipitated and the oil maintained in fluid condition, centrifuging the chilled products with a heavier carrier liquid and separately discharging from the centrifuge the separated wax and the wax freed oil.

4. The method of treating a residue containing wax in the "intermediate" form, which consists in steam distilling off a portion of such residue without changing the character of the wax substantially, diluting the distillate with a lower boiling point petroleum distillate beyond the point of saturating the wax, chilling the diluted product so as to precipitate the wax, centrifuging the chilled product with water as a carrier liquid, separately discharging the wax and the wax freed oil, and distilling the wax freed oil to separate the diluent therefrom.

5. The method of obtaining lubricating oils from petroleum which comprises distilling the petroleum with fractionation thereof and the separation of a fraction containing lubricating stock together with wax in the "intermediate" form, diluting such fraction with naphtha, so as to render the oil sufficiently lighter than the wax to permit their separation by centrifugal force, chilling the diluted product so as to precipitate the wax while retaining the oil in its fluid condition, and centrifuging the chilled product so as to effect the continuous separation and separate discharge of the oil and the wax separated therefrom.

6. The method of obtaining lubricating oils from petroleum which consists in distilling the petroleum with isolation of a distilled lubricating stock, distilling the lubricating stock with the production of a resi-

due comprising the bulk thereof, the distillations being effected without substantially cracking the oil, diluting the residue with naphtha so as to render the oil sufficiently lighter than the wax to permit continuous centrifugal separation thereof, chilling the diluted product gradually with precipitation of the wax while maintaining the fluidity of the oil, and centrifuging the chilled product so as to effect the separation of the wax and oil.

7. The process of producing lubricating oil which comprises the distillation of the lubricating portion of petroleum so as to leave a residue containing "amorphous" wax, separating the distillate into fractions containing wax in the "crystalline" and in the "intermediate" forms respectively, diluting the fraction containing the "intermediate" wax with naphtha so that the oil shall have a lower specific gravity than the wax, chilling the diluted product without substantial agitation, so as to precipitate the wax while retaining the fluid condition of the oil, and centrifuging the chilled product so that the oil and wax are separated and separately discharged.

8. The process of treating a petroleum product containing wax in the "intermediate" form which consists in diluting said product with naphtha of not heavier than 65° Bé., chilling the diluted product, and centrifuging the chilled product to discharge the wax and the oil separately.

9. The process of treating a petroleum product containing wax in the "intermediate" form which consists in diluting said product with naphtha, chilling the diluted product to a temperature below zero F. while maintaining the fluidity of the oil, and centrifuging the chilled product to discharge the wax and the oil separately.

Signed at Philadelphia, in the county of Philadelphia and State of Pennsylvania, this third day of April, 1922.

PHILIP T. SHARPLES.
